UNITED STATES PATENT OFFICE.

EUGENE B. FREW, OF TITUSVILLE, PENNSYLVANIA.

GAS AND WATER PACKER FOR OIL-WELLS.

SPECIFICATION forming part of Letters Patent No. 295,747, dated March 25, 1884.

Application filed August 18, 1883. (No model.)

To all whom it may concern:

Be it known that I, EUGENE B. FREW, a citizen of the United States, residing at Titusville, in the county of Crawford and State of Pennsylvania, have invented a new and useful Gas and Water Packer for Oil-Well or Artesian Wells, of which the following is a specification.

My invention relates to the casing inserted in the well to prevent the water from the upper strata of rock from flowing down the well into the oil-producing stratum, and also to the packer used to confine the gas in the well, the object being to combine them both in one contrivance and make that contrivance very much cheaper and more effectual than the devices at present in use.

The present method of drilling and tubing oil-wells is as follows:

First, a conductor-pipe is driven or dug down to the solid rock, this conductor-pipe being either a wooden box or an iron pipe about eight inches in inside diameter. Below this the hole is drilled, about seven inches inside diameter, until the drill passes through all the water-producing strata, when the "casing" is put in, which is a string of pipe usually five and five-eighths inches inside diameter, reaching from the surface to the bottom of the well as far as now drilled, and resting on the rock on the present bottom. The length of this casing varies in the different wells, according to the depth at which the lowest water-producing stratum is found, from one or two hundred to two thousand feet. Through this five and five-eighths casing a small hole is drilled to the oil-producing rock, the casing resting on the shoulder left between the larger and smaller hole, and effectually cutting off the flowage of water into the lower part of the well. After the drilling is completed, the "tubing" is inserted, which is a smaller string of pipe reaching from the surface to the oil-producing rock. Around this tubing, and above the oil-producing rock, is placed a "packer," generally a cylinder of rubber, to entirely fill the space between the outside of the tubing and the walls of the well. This prevents the escape of gas around the tubing, the gas then exerting a pressure upon the surface of the oil and forcing it up through the tubing, producing what is called a "flowing well."

By my device I claim to produce the same results as are now produced by the casing and the packer described above.

My device is illustrated in the accompanying drawings, in which Figure 1 is a sectional view, showing tubing as having a short sliding motion through the head of the casing, and Fig. 2 showing the tubing as fixed to the casing-head.

Similar letters refer to similar parts.

A represents the walls of the well of the greater diameter; B, the walls of the well of the lesser diameter; C, the rock shoulder between the two diameters; D D, the tubing.

E is a joint of casing, open at the lower end, the upper end being filled by the casing-head or plug F. In Fig. 1 this plug is shown as having an opening, O, in the center of slightly greater diameter than the outside of the tubing D, and through which a section, G, of the tubing plays.

H I are collars on the tubing above and below the plug F, and are of greater external diameter than the opening O. This arrangement allows of a free vertical motion of the tubing through the plug F between the collars H and I. The plug F is recessed upon its upper surface to receive the collar H, and in this recess the packing-ring K is inserted.

In use, when the well is being tubed, at the proper place in the tubing D the section G is inserted with its external appliances of the plug F and joint of casing E suspended from it and upheld by the collar I. The tubing is lowered into the well until the lower end of the casing E rests on the shoulder C in the wall of the well. The further progress of the casing is arrested and the tubing D follows down until the collar H engages with the plug F and rests upon the packing-ring K. The whole weight of the tubing then rests upon the plug F, and consequently upon the casing E, pressing it down to a firm seat upon the shoulder C, making it a watertight joint. The lower edge of the casing E may be sharpened, if desired, as shown in the drawings, so as to more effectually cut its seat into the rock. Water is thus prevented from flowing downward around the casing, while the collar H, resting on the packing-ring K, prevents it from passing inside the casing, and it is shut off from the bottom of the well, and at the same time the hydrostatic pressure upon the

100

top of the plug F is more firmly seating the lower end of the casing upon the seat C and holding the packer in place against the pressure of gas from below.

5 While the packer prevents the water from passing down, it also cuts off the escape of gas upward around the tubing D, and compels it to exert its pressure upon the surface of the oil; as in the ordinary packer.

10 On lifting the tubing from the well, the tubing is first lifted, freeing the collar H from the plug F, when the water is allowed to flow down through the annular space around the tubing into the well, in that manner relieving the wa-

15 ter-pressure on the plug F. After the water-pressure is removed, the whole appliance is drawn from the well. Fig. 2 in the drawings illustrates the same device, only the tubing is rigidly attached to the plug F, dispensing with 20 the collars H and I, the slip-joint G, and the packing-ring K. In this the casing must be raised from its seat before the water-pressure is relieved.

This packer must be at some point between 25 the lowest water-bearing stratum and the top of the oil-bearing rock, and may be at any point between the two as may be desired at the drilling of the well, the only precaution being to make the shoulder C at the point where it is 30 desired to place the packer.

I claim as my invention—

1. The casing E, seated upon the shoulder C,

and having at its top end the plug F, forming a water-tight joint between the casing E and the tubing D, as a device for shutting off the 35 water from the bottom of an Artesian well, substantially as described.

2. In oil or Artesian wells, a combined gas and water packer, consisting of a joint of casing, and a pipe larger than the tubing of the well, the 40 lower end of said casing being seated on a shoulder in the rock walls of the well, and the upper end being fitted with a plug or reducer to entirely fill the annular space between the top of the casing and the tubing, substantially as de- 45 scribed.

3. A gas and water packer for oil and Artesian wells, consisting of the joint of casing E, seated at the lower end on the seat C in the rock wall of the well, and having at its upper 50 end the plug F, said plug fitting loosely around the joint G of the tubing D, in combination with the joint G of the tubing D, said joint having the collars H and I above and below the plug F, the collar H engaging with a recess in 55 the plug F, the joint between being packed and made water-tight by the packing-ring K, and the whole weight of the tubing resting on the plug F, the whole constructed substantially as described, and for the purposes herein set forth. 60

EUGENE B. FREW.
